FOREIGN PATENT DOCUMENTS

WO WO 2013/172783 A1 11/2013

Primary Examiner — Keli L Hill(74) *Attorney, Agent, or Firm* — Baker & Hostetler LLP(57) **CLAIM**

The ornamental design for a necked beverage can, as shown and described.

DESCRIPTION

FIG. 1 is a top perspective view of a necked beverage can according to a first embodiment of our new design;

FIG. 2 is a front view thereof, the front view being identical to the rear view, the left side view, and the right side view;

FIG. 3 is a top plan view thereof;

FIG. 4 is a bottom plan view thereof;

FIG. 5 is a top perspective view of a necked beverage can according to a second embodiment of our new design;

FIG. 6 is a front view thereof, the front view being identical to the rear view, the left side view, and the right side view;

FIG. 7 is a top plan view thereof;

FIG. 8 is a bottom plan view thereof;

FIG. 9 is a front view of a necked beverage can, according to a third embodiment of our new design, the front view being identical to the rear view, left side view and right side view;

FIG. 10 is a top plan view thereof;

FIG. 11 is a bottom plan view thereof; and,

FIG. 12 is a top perspective view thereof.

The broken lines in the drawings are to illustrate environment only and form no part of the claimed design.
